FLAPPING WING FLIER FOR INDIVIDUAL FLYING

Maria Mackiewicz, New York, N. Y.

Application June 10, 1950, Serial No. 167,353

5 Claims. (Cl. 244—28)

1

This invention relates to an improved flying device or machine, and embraces the combination of a bag, or balloon, filled with a buoyant gas, such as helium, and manually operated wings supported by the buoyant gas bag, which can be manipulated to control the vertical position of the person using the device or machine for aerial flight, and to produce horizontal travel motion through the air.

One of the objects of the invention is the provision of a safety flying device, which can be used for transferring a passenger from an aeroplane to the ground, or for aerial flights from high altitudes to lower altitudes, by the manual operation of wings strapped to the body, and connected with the wrists of the passenger, so that flapping motions may be generated, simulating the natural flight movements of a bird, while the main load of the body of the passenger is supported by a buoyant bag filled with non-explosive helium gas, so that maximum directional effect will be obtained from the manual operation of the flapping wings.

Another object of the invention is to provide a flying device with wings which are buoyant, and which can be filled from a central valve control, but which are constructed to provide buoyant radial ribs.

With the above and other objects in view the invention comprises certain new and useful constructions, combinations, and arrangements of parts, clearly described in the following specification, and fully illustrated in the drawings, in which:

Fig. 1 is a bottom plan view, showing the manner of strapping a passenger to the wings and the buoyant gas bag.

Fig. 2 is a front elevation thereof.

Fig. 3 is a bottom plan view before the passenger is strapped into flight position.

Fig. 4 is a front end elevation thereof.

Fig. 5 is a fragmentary vertical sectional view through the buoyant gas bag and one of the buoyant wings, showing the body holding straps thereof, taken on line 5—5 of Fig. 3, enlarged.

Fig. 6 is a transverse sectional view through one of the buoyant wings, taken on line 6—6 of Fig. 3, looking in the direction of the arrows.

Fig. 7 is a plan view of a pattern used for the construction of the wing, before the pattern has been gathered to provide gas holding compartments or chambers.

Fig. 8 is a fragmentary edge view of one of the wings.

Fig. 9 is a detail sectional view, showing a

2

concealed strap, and body straps connected thereto.

Referring to the accompanying drawings, which illustrate the practical construction of the invention, 10 designates a gas bag for holding helium gas, which has an envelope constructed of gastight rubberized fabric or similar material, and which may be of any desired shape or form, but of a capacity to carry the load of the average passenger, or nearly so, when properly inflated with helium gas.

The lower end of this gas bag is closed, and gas is supplied to the bag, and released from the bag, through one or more control valves 11, one or more of which may be equipped with a release pull cord 12, to permit of distant operation, so that the buoyancy of the gas bag may be regulated by the passenger during flight or before flight, or after flight.

At one side of the bottom of the buoyant gas bag 10 a wing 13 is attached to the lower edge of a flap 13' and the upper edge of said flap 13' is connected by a flexible hinge joint 14' to said bag 10 by a flexible hinge joint 14. At the opposite side of the bottom of the gas bag another and similar wing 15 is attached by a flexible joint 16 a flap 15' and a flexible joint 16'. Since each wing is constructed in duplication of the other, one only need be described in detail.

Each wing is formed so that it will have a triangular shape, when viewed edge wise from the front or rear end of the device, with the wider end of the triangular shaped wing located outermost. Each wing comprises an upper layer of rubberized sheet material 17, and a lower layer or similar material 19, each layer having the initial shape shown in the pattern 20, of Fig. 7. The outer edges of the two layers 17 and 19 are united by bonding or vulcanization to the edge strip or wall piece 21, so as to provide a hollow wing structure. This hollow wing structure is then subjected to pressure and bonding operations along radial lines 23 (Fig. 1) to divide each hollow wing into hollow radial ribs

22 connected at their open outer ends to a common chamber 21a (Fig. 5) and at their inner open ends to a common chamber 23a (Fig. 5) provided with a control valve 24, suitably mounted in the lower layer 19 of the wings.

Through each valve 24 helium or other buoyant gas may be supplied to the interior of the corresponding wing, or may be discharged as desired.

Each flap is provided at its lower hinge joint with a strap 25, which is attached thereto in any

suitable manner. To this strap 25 the body holding straps are positively connected, as by vulcanization.

The body holding straps of each flap include a strap 26 for use through the arm pit over the shoulder, a strap section 27 for use to hold the chest of the passenger, strap 28 for the thigh, a strap 29 for the knee and strap 30 for the ankle. The strap section 27 at the two flaps cooperate to hold the chest of the passenger in proper position.

Each wing is further provided with a plurality of operating cords 31, of nylon, linen, cotton or other material, which are connected at their outer ends to grommets 32, secured in any suitable manner to the semi-circular tip of the wing, and which converge radially to a slip ring 33, through which all of the operating cords extend. This slip ring is provided with a single pull cord 34, formed into a loop 35, and provided with a slip ring 36 for regulating the size of the loop. This loop is placed around the wrist of the arm and the slip ring is tightened, so that proper coupling between the arm and the pull cord 34 is established. The radial cords 31 perform the function of shroud lines of a parachute, and distribute the pulling effort imposed manually by the single operating cord 34 equally over the tip of the wing.

The passenger is supported by said straps 26, 27 and 28 between the inner edges of the two wings, below the bottom of the buoyant gas bag. The lifting force of the buoyant gas bag and of the two wings, which are also buoyant, may be sufficient to support the passenger without the lifting effort generated by the manual flapping of the wings, or regulated so that the combined lifting effort of the wings when properly manipulated and the gas bag will be required to prevent gravitational descent.

The gas bag may be inflated so that it will produce a rising motion of the device and its passenger at the time of the take-off, or regulated so that a slow descent from a high elevation may be made.

It is possible for the passenger to control the direction of descent or of horizontal flight, by manipulating or flapping one wing, while holding the other wing motionless, as indicated in dotted lines in Fig. 2. In this case the manipulated wing will function as the propeller and the stationary wing will act as the rudder of the flying device.

As the wings are buoyant they may be operated by the passenger to produce a bird-like flapping motion, up and down, with minimum of physical exertion.

My invention can be used in place of conventional escape parachutes, to transfer passengers from disabled aeroplanes to safe ground position, or from high mountain elevations to safety below, or for sport flying.

It is understood that various changes may be made in the details of construction, their combination and construction, arrangement of parts, set forth in the claims hereof, which define the invention.

Having described my invention I claim as new:

1. A flying device, comprising a gas bag having a passenger lifting effect, a pair of wings each having a straight inner edge and a curved outer edge, means for connecting said wings, to the bottom of the gas bag including hinges at the inner edges of said wings, straps for securing the body of a passenger to the connection between the wings and the gas bag, radial operating cords connected with the outer edges of the wings, and means for connecting the arms of the passenger to the radial operating cords to enable the passenger to shift said wings.

2. A flying device, comprising a gas filled bag having a passenger lifting effect, a pair of wings with curved outer edges and filled with buoyant gas, including hinges at the inner edges of said wings, means for strapping a passenger to the connection between the wings and the gas bag, and pull cords connected with the outer edge of each wing and having means connectable to a wrist of the passenger, to enable the passenger to produce a swinging movement of the wings.

3. A flying device, comprising a gas filled bag having a passenger lifting effect, a pair of buoyant-gas-filled wings having flexible hinge connection with the lower end of the gas bag, including hinge means at the inner edges of said wings, each of said wings having radial hollow ribs and a connecting chamber at their inner ends, said chamber having a valve for use in inflating or deflating the wing, body straps attached to the connections between each wing and the gas bag, said body straps including an arm pit strap, a chest strap, a thigh strap, a knee strap and an ankle strap, a plurality of radial pull cords attached at their outer ends to the outer edges of said wings, and a single pull cord connected with all before mentioned cords on each wing, whereby a passenger coupled by means of said body straps to the gas bag can produce motion of either or both wings.

4. A flying device according to claim 1 wherein said means for connecting said wings to the bottom of said bag includes flaps each connected at one edge to said hinge at the inner edge of the corresponding wing and at the opposite edge to said bag.

5. A flying device according to claim 2 wherein in each wing comprises radial triangular chambers of greater thickness at their outer ends.
